UNITED STATES PATENT OFFICE.

CARL G. OLSON, OF CHICAGO, ILLINOIS, ASSIGNOR TO ILLINOIS TOOL WORKS, OF CHICAGO, ILLINOIS, A CORPORATION OF ILLINOIS.

LAPPING-MACHINE.

1,360,435.

Specification of Letters Patent. Patented Nov. 30, 1920.

Application filed May 24, 1919. Serial No. 299,589.

To all whom it may concern:

Be it known that I, CARL G. OLSON, a citizen of the United States, residing at Chicago, in the county of Cook and State of Illinois, have invented a certain new and useful Improvement in Lapping-Machines, of which the following is a specification.

This invention relates to machines intended primarily for rubbing or lapping the teeth of milling cutters, especially that type of cutter used for cutting gear teeth and commonly known as gear cutting hobs. The general object is to provide a machine capable of producing a hob having the same qualities as a ground hob. Another object is to provide a machine capable of lapping all of the hob teeth at the same time, thus greatly reducing the amount of time required to finish the work. Another object is to provide a construction capable of producing substantially perfect uniformity of the hob teeth. Another object is to render the machine largely automatic in its nature, thus saving time and labor on the part of the attendant. Contributory objects, by which these main objects are carried out, will become apparent as the description proceeds.

I accomplish my objects by the mechanism illustrated in the accompanying drawings, in which—

Figure 1 is an end elevation of the machine looking toward the left in Fig. 2.

Fig. 2 is a side elevation of the machine, chiefly in section on the line 2—2, Fig. 1.

Fig. 3 is a sectional elevation on the line 3—3, Fig. 1.

Fig. 4 is a side view of one of the lap holders and associated parts.

Fig. 5 is a detail illustrating the manner by which the cam plate may be utilized to hold the lap out of contact with the hob.

Fig. 6 is a detail view illustrating the manner in which the laps and other holders are arranged around the hob and also illustrating the oscillatory movement made by the hob during the active operation of the machine.

Fig. 7 is a fragmentary detail illustrating the movement which occurs in the lap holder during the oscillatory movement of the hob.

Like numerals denote like parts throughout the several views.

In the form of machine shown in the drawings for illustrating the principle of the in-

vention the main shaft 1 is journaled in a bearing 2 and a sleeve 3, said bearing being supported upon the column 4 rising from the base plate 5 of the machine. The sleeve 3 is journaled in a bearing 6 which is supported upon a column 7 also rising from said base plate. The work 10 which is shown in the form of a hob is rigidly fastened to shaft 1 in any suitable manner. Said shaft may, therefore, be regarded as the work holder.

The main shaft or work holder is designed to oscillate through a comparatively narrow angle—for example, an angle considerably narrower than the one subtended by a single tooth of the hob. This oscillatory movement of the work holding shaft is produced by means of an index plate, best shown in Figs. 2 and 3. This plate has a sleeve 13 which encircles the shaft, and is prevented from moving lengthwise of the shaft by being confined between the bearings 2 and 6, previously mentioned.

The plate and sleeve are splined to the shaft by means of a feather 14, the keyway 15 in the shaft being considerably elongated in order to permit the shaft to shift longitudinally, at the same time that it rocks. The index plate 12 is oscillated by means of a rocking member 17 which encircles and rests upon sleeve 13 and has an arm 18 carrying a detent 19, the lower end of which is adapted to enter the various notches 20 formed in the periphery of the plate. Said detent is normally urged toward the plate by means of a spring 21. The rocking member 17 has an arm 23, the lower end of which is vertically slotted or bifurcated to receive an eccentric 24 formed upon shaft 25. Said shaft is journaled in a bearing 26 formed in the column 4, and is driven by a pulley 27, or other suitable power device, with the result when the shaft 25 is rotated, it will cause the member 17 to oscillate, and the latter, acting through detent 19, will cause the index plate 12 and shaft 1 to oscillate.

Rising from and preferably integral with the bearing 6 is a bracket 30. Adjacent to it on the side opposite to the index plate 12 is a face plate 31 which is here shown to be integral with sleeve 3 and is prevented from rotating by means of a pin 32 (best shown in Figs. 2 and 5). This pin passes through the face plate into the bracket 30 and is thus

prevented from rotating. Rigidly fastened to the face plate 31 by nuts 34 or otherwise, are posts 35 equal in number to the hob teeth. Each of these posts forms a pivotal support 5 for an arm 36 which, in the present case, is yoke shaped, and is provided with two branches 37, 37. As shown in detail in Fig. 4, these branches carry conically pointed pins 38, 38 which form centers for supporting the lap holders 40. The lap holders are also U-shaped in the present design and support the laps 41 which are held in position by tap screws 42, 42 or other appropriate devices. In order to prevent the lap holders 10 from rotating too far about their center pins 38 they are provided with a stop pin 44 which screws into one side of the lap holder and passes out through an elongated slot 45. The laps are of lead or other soft metal or 20 alloy and are accurately formed, their active surfaces being configurated to accurately fit properly formed hob teeth. The laps are by preference in the form of flat blocks of a length one or two notches longer 25 than the hob which is to be treated. The purpose of this is to enable the laps to engage both sides of all of the hob teeth no matter which set or row of teeth are being acted upon.

30 The laps are pressed toward the work by means of springs 48 which in the preferred construction take several turns around the respective posts 35, one end being brought out so as to back up the arm 36 and the 35 other end being brought out so as to engage the respective pins 49 projecting laterally from the cam ring 50. Said ring encircles the face plate 3 and makes sliding contact with the periphery thereof. It is held in 40 position on the plate by means of a flat ring 51. Its angular position is governed by a handle 52 having a base 53 which is fastened to said ring by means of screw 54, or otherwise. The bracket 30, previously 45 mentioned, has a segmental plate 57 at the upper end, having a row of apertures 58, centered at the axis of shaft 1.

A pin 59 carried by the handle 52 is 50 adapted to enter into one of the apertures 58 and hold the cam ring 50 in the desired angular position. Said cam ring has a cam 60 for each of the arms 36. These cams are adapted to cooperate with tails 61, extending 55 from each of the arms 36 in such manner that when the cam plate is angularly shifted toward the left, Fig. 5, the cams will engage the parts 61 and rotate the arms 36 in such direction as to retract the laps from the hob, as shown in Fig. 5. When 60 the laps and their supporting parts are thus held in retracted position, the hobs may be readily removed from or positioned upon the work holder. When the cam plate is shifted angularly toward the right, the cams 65 will free the tails 61 and permit the springs

48 to bring the laps into close contact with hob.

In operation, after the hob or other cutter has been fastened upon the work holder the operator retracts the pin 59 and shifts 70 the cam ring toward the right, Fig. 5, to permit the cams 60 to release the parts 61 and permit the springs 48 to press the laps against the hob. When the arms 36 are thus released the operator inserts pins 59 75 into the proper aperture 58, whereupon the machine may be started.

The pulley 27, in rotating, causes the eccentric 24 to rock the element 17 about the main shaft 1 and this, acting through the 80 index plate 12, causes the shaft to oscillate and oscillate the hob. As the hob teeth are arranged helically it is evident that the rotary movement of the hob, even though confined to a small angle, produces a movement 85 of the hob in an axial direction. This is arranged for, however, for shaft 1 which constitutes the work holder is slid able longitudinally in its bearings and in the sleeve 90 13 of the index plate. Hobs, of course, have relieved teeth—that is, their outer surfaces are not concentric with the axis of the hob, but are eccentric. The result is that the oscillatory movement of the hob produces a vibratory movement of the arms 36 about 95 their pivot posts 35. The springs 48, however, keep the laps at all times pressed against the surface of the hob teeth, thereby producing a rubbing action, thus rubbing down or “lapping” the surfaces of the hob 100 teeth to bring them to perfect and accurate configuration. Although the arms 36 vibrate to compensate for the relief of the hob teeth, there is produced, in addition, an oscillation of the laps about their pivot pins 105 38 as illustrated in Fig. 7. This enables the machine to accommodate hobs of different sizes and hobs having different ratios of relief. The axial point of the lap holder is 110 so located with respect to the teeth of the lap that the pressure of the lap upon the hob teeth will be substantially uniform at all points of the surface of the hob teeth. I have found that it desirable, in order to secure 115 this effect, to so construct the parts that the axis of oscillation of the lap holder—i. e., the center line of the pins 38, will pass through what may be regarded as the pitch line of the lap teeth, half way between the front and back of the lap; in other words, the axis of oscillation is centered with respect to the thickness of the lap and lies substantially in the pitch circle of the lap teeth. Although the lap holders are thus 120 free to oscillate about their center pins 38, said holders will not swing far out of position when the arms 36 are in retracted position (see Fig. 5). The stop pins 44 will strike the end of the slots 45 formed in one of the branches 37 of arms 36; in fact, the 125 130

construction is such that the laps will have free play so far as necessary to maintain good contact with the hob teeth, but will never swing so far away from acting position that they will not automatically resume acting position when the arms 36 cause them to approach the hob. After the laps have been in contact with one set of teeth for a short time, the operator stops the machine, 10 rotates the cam ring 50 so as to retract the laps from the hob teeth, retracts the detent 19 from the index plate 12 and, grasping the knurled head 65 of shaft 1, rotates the index plate one notch thus bringing a fresh 15 row of hob teeth under each of the laps. He then lowers the detent so as to hold the index plate in engagement with the oscillating arm 18, and rotates the cam ring 50 so as to release the arms 36, thus bringing the 20 laps into contact with said fresh row of hob teeth. The machine is then started up again and operated for another short interval, after which the operator goes through the same performance and brings still another 25 row of teeth into contact with the laps. This performance may be repeated as many times as desired, but in any event the result will be to produce practically perfect accuracy in the teeth. It will be evident 30 that if a given hob tooth has a particularly high point it would ultimately affect the lap in contact with it in case the entire lapping operation were completed without angularly shifting the hob; but by thus bringing the 35 laps successively into contact with different rows of teeth, the laps will wear uniformly and will produce uniformity in the hob teeth. It will be understood, of course, that the hobs are fairly accurate before they are 40 brought to the lapping machine, as is the case when hobs are finished in a grinding machine, hence, it is expected that only the final truing of the teeth need be accomplished, and this is accomplished with my 45 machine practically to theoretically complete perfection.

During the lapping operation the contacting surfaces are supplied with a lubricant with which is mixed powdered carborundum or other abrasive. I have found by experience that the carborundum particles apparently become embedded in the acting surface of the laps and on this account and on account of the presence of the lubricant the 50 wear upon the laps is much less than might be expected. Hence it is possible to configure the laps very accurately to the size which the finished hob teeth must conform to, and the laps last much longer before becoming excessively worn than might be anticipated.

One of the great advantages of my machine over an ordinary hob grinding machine is that it is capable of acting upon 55 all of the hob teeth simultaneously instead

of one at a time as with the ordinary grinding machine. Thus the time required for finishing the hob is greatly reduced. This, taken in connection with the great accuracy with which the hob teeth are formed, renders the machine of great value in connection with the production of hobs and similar gear cutters. 70

Having thus described my invention what I claim as new and desire to secure by Letters Patent, is:

1. A machine for lapping hobs having a work holder for supporting the hob, a plurality of laps encircling the hob, and means for causing relative angular movement between the laps and hob, the work holder and the laps being adapted to move relatively in a direction parallel to the axis of the hob, the laps being adapted to engage opposite sides of the hob teeth whereby 85 the lead of the hob teeth causes relative reciprocation in a direction parallel to the axis of the hob.

2. A lapping machine having a work holder adapted to support a hob, a lap 90 adapted to engage the teeth of the hob, means for causing relative angular movement between the lap and the hob, the lap and the hob being relatively movable in a direction parallel to the axis of the hob, 95 and a lap holder pivotally mounted so as to accommodate the eccentricity or relief of the hob teeth.

3. A lapping machine having a work holder adapted to support a hob, a lap 100 adapted to engage the teeth of the hob, means for causing relative angular movement between the lap and the hob, the lap and the hob being relatively movable in a direction parallel to the axis of the hob, 105 and means for yieldingly pressing the lap against the hob teeth.

4. A lapping machine having a work holder which is oscillatable about a fixed axis, means for oscillating it rapidly about 110 its axis, a plurality of laps arranged approximately radially about the axis of the work holder, a holder for each of the laps, and an arm for each of the lap holders, the lap holders being pivotally mounted 115 in their respective arms, and means pivotally supporting said arms.

5. A lapping machine having a work holder which is both oscillatable and axially shiftable, a plurality of laps adapted 120 to rub the work, and a holder for each of the laps, and an arm for each of the lap holders, the lap holders being pivotally mounted in their respective arms, and means for pivotally supporting said arms. 125

6. A lapping machine having a shaft adapted to support the work, means for oscillating said shaft about its axis, laps arranged approximately radially about the axis of the shaft, lap holders for said laps, 130

- arms in which said lap holders are pivotally supported, posts on which said arms are pivotally supported, and springs for forcing the laps toward the work.
- 5 7. A lapping machine having a shaft adapted to support a hob, said shaft being longitudinally shiftable, means for oscillating said shaft about its axis, laps arranged approximately radially about the shaft, 10 said laps having teeth adapted to engage the hob teeth, lap holders for said laps, arms having pivot pins for pivotally supporting the lap holders, the axis of said pins being located approximately at the 15 pitch circle of the lap teeth, and means for supporting said arm and simultaneously urging them toward the work.
8. A lapping machine having a work holder, adapted to support milling cutters, 20 hobs, and similar substantially cylindrical objects, a lap adapted to engage the hob teeth, a pivotally supported arm adapted to support said lap, a cam adapted to hold said arm in non-acting position, and means 25 for positioning said cam.
9. A lapping machine having a work holder adapted to support milling cutters, hobs, and similar substantially cylindrical objects, a plurality of laps arranged radially about the axis of the work holder, lap 30 holders, arms for pivotally supporting said lap holders, said arms being adapted to move the laps toward and from the work, and means for limiting the amount of rotation of the lap holders relatively to said arms.
10. A lapping machine having an oscillating shaft adapted to support milling cutters and the like, a face plate arranged 40 at right angles to the shaft, concentric therewith, posts extending from the face plate parallel to the shaft, arms pivoted on said posts, and laps pivotally mounted in said arms in position to engage the teeth of the 45 work.
11. A lapping machine having an oscillating shaft adapted to support milling cutters and the like, a face plate arranged at right angles to the shaft, concentric therewith, posts extending from the face plate parallel to the shaft, arms pivoted on said posts, laps pivotally mounted in said arms in position to engage the teeth of the work, and springs anchored at one end to the face 55 plate and the other end to said arms for yieldingly holding the laps in engagement with the work.
12. A lapping machine having an oscillating shaft, adapted to support hobs and 60 the like, a face plate arranged at right angles with the shaft concentric therewith, posts extending from the face plate parallel to the shaft, arms pivoted on said posts, laps pivotally mounted on the said
- arm in position to engage the teeth of the work, said shaft being longitudinally shiftable to accommodate the lead of the hob teeth, and springs adapted to urge the laps toward the work.
13. A lapping machine having a work holder adapted to support substantially cylindrical cutters having relieved teeth, laps adapted to act upon the teeth of the work, supporting members in which said laps are pivotally mounted to enable them to automatically maintain surface contact with the teeth of the work, and means for producing a reciprocating relative movement between the laps and the work, approximately in an arc centered at the axis of the work.
14. A lapping machine having a work holder adapted to support a hob, a lap for rubbing the hob teeth, a supporting member for the hob, means for producing relative reciprocatory movement between the hob and the laps in an arc centered at the axis of the hob, and pivots for supporting the lap in the supporting member, said lap having teeth mating with the hob teeth for making surface contact therewith, and the axis of the pivots passing substantially through the pitch circle of the lap teeth.
15. A lapping machine having a work holder, a rotatable shaft for actuating the work holder, an index plate, actuating means adapted to engage said index plate for oscillating it, said plate being adapted to oscillate the shaft and being angularly adjustable with respect to said actuating means, a lap and means for holding said lap in contact with the work.
16. A lapping machine having a work holder adapted to support a hob, a rotatable shaft for actuating the work holder, an index plate splined to said shaft, actuating means adapted to oscillate said index plate, said plate being angularly adjustable relatively to said actuating means, a lap adapted to engage the teeth of the work, and supporting means for holding said lap in contact with the hob teeth, said supporting means being adapted to hold the lap against movement in a direction parallel to the shaft and adapted to permit the lap to assume different positions in a plane transverse to the axis of the hob to enable it to maintain contact with the relieved hob teeth.
17. A lapping machine having a shaft adapted to oscillate about its axis, said shaft being adapted to support a hob coaxially, an index plate splined to said shaft, an eccentric located at a point remote from the axis of the shaft, means for rotating said eccentric, a connecting member actuated by said eccentric and adapted to oscillate the index plate about its axis to thereby oscillate the shaft, said index plate being angularly ad-

justable with respect to said connecting member, a lap, and means for holding said lap in contact with the hob teeth.

18. A lapping machine having a shaft adapted to oscillate about its axis, said shaft being adapted to support a hob coaxially, an index plate splined to said shaft, an eccentric located at a point remote from the axis of the shaft, means for rotating said eccentric, a connecting member actuated by said eccentric and adapted to oscillate the index plate about its axis to thereby oscillate the shaft, said index plate being angularly adjustable with respect to said connecting member, and a lap adapted to engage and rub the hob teeth, said lap being held against movement parallel to the shaft and being adapted to move relatively to its support for enabling it to maintain surface contact with the teeth of the hob.

19. A lapping machine having a work holder, a shaft adapted to actuate the work holder, an index plate adapted to oscillate said shaft, said plate having a hub, an actuating member journaled on said hub and adapted to engage said index plate at chosen points on its circumference, means for oscillating said actuating member, a lap, and means adjacent to the work holder for holding the lap in contact with the work.

20. A lapping machine having a work holder, a shaft adapted to actuate the work holder, an index plate adapted to oscillate

said shaft, an actuating member adapted to engage said index plate at different points on its circumference, an eccentric, remote from the shaft and adapted to engage said actuating member for oscillating the index plate, means for rotating said eccentric, a lap, and means for holding the lap in contact with the work.

21. A lapping machine having a work holder, a shaft adapted to actuate the work holder, an index plate adapted to oscillate said shaft, said plate having a hub, an actuating member journaled on said hub and adapted to engage said index plate at chosen points on its circumference, an eccentric located at a distance from the shaft for oscillating said actuating member, a lap, and means adjacent to the work holder for holding the lap in contact with the work.

22. A lapping machine having a work holder adapted to support cutters having relieved teeth, laps for rubbing the teeth, and supporting members for moving the laps practically radially with respect to the cutters, said laps being pivotally mounted in said supporting members and having a free and independent motion in the supporting members whereby the laps are able to automatically maintain surface contact with the teeth of the work.

In witness whereof, I have hereunto subscribed my name.

CARL G. OLSON.
